UNITED STATES PATENT OFFICE.

FRANK O. ADAMS, OF SPOKANE, WASHINGTON, ASSIGNOR TO SUCCESS CONCRETE
NO-ICE FOOD COOLER CO., OF SPOKANE, WASHINGTON.

ICELESS FOOD OR LIKE COOLER.

1,372,471.

Specification of Letters Patent. Patented Mar. 22, 1921.

Application filed October 20, 1919. Serial No. 331,917.

To all whom it may concern:

Be it known that I, FRANK O. ADAMS, a citizen of the United States, residing in Spokane, in the county of Spokane and State 5 of Washington, have invented certain new and useful Improvements in Iceless Food or like Coolers, of which the following is a specification.

This invention relates to improvements in 10 food or like coolers of that class wherein the lowering of the temperature therein is accomplished by evaporation resulting from the moistening of the walls of the cooler.

One of the objects of the invention is to 15 provide a device of the class described wherein in the water storage means and the water feeding means are self contained with respect to the cooler as a whole.

Another object of the invention is to 20 provide a device of the class described wherein means are provided for the assured moistening of the entire area of the side walls. The novel means for accomplishing this consists in the provision of a water reservoir positioned approximately at the top of the walls 25 of the cooler and means whereby water contained in the reservoir is fed downwardly into said walls.

Another object is to provide a device of the 30 class described wherein it is unnecessary to impregnate the bottom or walls of the cooler with a waterproofing substance, thereby evading the possibility of an unpleasant or unhealthful odor within the cooler.

A still further object is to provide a device 35 of the class described wherein the cover comprises an independent cooling unit.

Still further objects and features of the 40 invention will be described in connection with the accompanying drawings and will be more particularly pointed out in and by the appended claims.

In the drawings:

Figure 1 is a perspective view of the exterior of my improved cooler.

Fig. 2 is a perspective view of my improved cooler cover, showing portions thereof broken away to illustrate details of construction.

Fig. 3 is a plan view of the cooler with the cover removed.

Fig. 4 is a section on line 4—4 of Fig. 3.

As illustrated, 10 designates a relatively shallow pan consisting of bottom 11, side 55 walls 12 and end walls 13 and 14. Pan 10 is

constructed of non-porous material such as metal, which may be proofed against the action of water. Snugly fitting within pan 10 is the cooling receptacle indicated generally at 15. Receptacle 15 consists of bottom 16, 60 side walls 17 and end walls 18 and 19. To reduce the weight of the entire receptacle 15 and yet allow the corners to retain sufficient strength, the walls 17, 18 and 19 are paneled as at 20. Receptacle 15 is constructed of concrete or like porous material and the mixture of this material is such that the walls 17, 18 and 19 will readily absorb and conduct water throughout their extent by capillary attraction. 70

I provide a reservoir 21 positioned around the top edge of receptacle 15 and preferably integral with and forming a part of the side and end walls 17, 18 and 19. Reservoir 21 is preferably constructed by the addition of 75 an upwardly turned flange 22 extending completely around the walls 17, 18 and 19. Flange 22 forms one wall of reservoir 21 while the completing wall is formed by the portion 23 of the upper edges of walls 17, 18 80 and 19. Flange 22 and portion 23 are constructed of concrete or like porous material identical with that comprising the rest of the receptacle 15 with the exception that the mixture of material making up said flange 22 85 and portion 23 is of such a nature as to render the walls of reservoir 21 of a lower degree of porosity than that of the remaining portion of walls 17, 18 and 19. The purpose of this variance in degree of porosity will be 90 hereinafter described.

A filler, overflow and water level indicating pocket is formed between pan 10 and wall 19 by pressing end wall 14 outwardly from end wall 19 as at 23'. A communicating 95 passage between the interior of receptacle 15 and pocket 23' is provided by coring out end wall 19 as at 24 (Fig. 4). End wall 19 is cut away as at 25 to facilitate the use of pocket 23' as a filler. The upper edge 100 of wall 14, where it forms the pocket 23', is turned down to form a lip 26 for a purpose to be hereinafter described.

A drainage port 27 leads outwardly from pocket 23' and is normally closed by cork 105 or like closure means 28.

I have generally indicated the cover of my cooling device at 29. Cover 29 consists of a pan 30 constructed of non-porous material such as metal. Running lengthwise of pan 110

30 and secured thereto by rivets 31, is the channel member 32 which strengthens the pan 30 and serves as reinforcement for the porous material 33, such as concrete, with 5 which pan 30 is filled. A handle 34 is secured to pan 30 and member 32 by rivets 34'. Material 33 is poured into pan 30 and allowed to set, the overturned edges 35 of pan 30 serving to protect the edges of material 10 33 and also maintain it within the pan.

By making the corners 15' of the receptacle 15 slightly lower than the rest of the receptacle, I provide a preferred means whereby there will be an air gap 29' at intervals 15 between the upper edges of the receptacle 15 and the bottom of cover 29 so that air may circulate through the cooler. This insures the maintenance of fresh, clean air within the cooler, thereby rendering it 20 sanitary and also hastening and then maintaining the lowered temperature within the cooler.

In first charging the cooler, I fill the reservoir 21 with water. I may also aid in the 25 initial charging by pouring water into chamber 39, formed by bottom 16 and the lower portions of walls 17, 18 and 19. This filling is preferably done through the pocket 23'. The water will then be drawn upwardly 30 from chamber 39 through the walls 17, 18 and 19 by capillary attraction, and will pass downwardly through the same walls from the reservoir 21 by capillary attraction aided greatly by gravity. Thus the entire area, 35 even to the topmost edges, will be quickly and thoroughly moistened with water, the subsequent evaporation of which will cool the interior of receptacle 15. After the initial charging it is only necessary to fill 40 reservoir 21 about once every twenty-four hours, enough water finding its way from reservoir 21 to chamber 39 to maintain the water level in chamber 39 practically constant.

45 At this point I wish to emphasize the fact that the filling of reservoir 21 at proper intervals and the moistening of cover 29 is the only attention that the attendant need give to the cooler to maintain it in a state of maximum efficiency. It will be seen that this 50 advantage is gained by the self contained features whereby the water storage and water feeding means for the receptacle 15 are one with the cooler itself.

55 The porosity of flanges 22 and portion 23 is such that they serve to regulate the feeding of water into the walls 17, 18 and 19 at just the right speed to maintain said walls in an even, moist condition. It will be seen 60 that were the degree of porosity of the reservoir 21 the same as that of the remaining portion of the walls 17, 18 and 19, the water would pass from reservoir 21 downwardly through the walls 17, 18 and 19 so rapidly 65 that the water in reservoir 21 would soon be

exhausted, with a resultant hastened drying of the said walls 17, 18 and 19, thereby greatly impairing the sustained cooling qualities and general efficiency of the cooler.

A cooler to be of any utility must have 70 such height as would preclude the use of a material having such a degree of porosity as would allow capillary attraction to draw water to its upmost edges in sufficient quantities to perform its cooling functions. It 75 will be seen that in my device gravity assists the passage of water downwardly from the reservoir 21 and insures the moistening of the entire surface of the cooler. Furthermore, the water in chamber 39 is constantly 80 assisting the moistening action throughout the lower portion of the cooler and if, for any reason, reservoir 21 becomes exhausted there is a supply of water in chamber 39 sufficient to maintain moistures in the walls 85 17, 18 and 19 to cause continued evaporation for a reasonable time, thereby saving the food contents of the cooler from spoiling until the reservoir 21 may be refilled.

The relative porosity of the walls of the 90 reservoir 21 and the walls of the receptacle 15 is such that, in actual practice, reservoir 21 need be filled but about once every twenty-four hours to maintain the walls 17, 18 and 19 evenly moistened and the water level 40 95 practically constant, thereby gaining maximum efficiency.

Inasmuch as pan 10 is composed of a non-porous material and the water line can never come above the top edge of pan 10 due to 100 passage 24 and pocket 23', it will be seen that it is unnecessary to water proof the interior of chamber 39, resulting in a saving of labor and eliminating the possibility of odor common to water proofing material. 105 Pocket 23' will serve as an overflow should the water level 40 rise within the receptacle 15 to a sufficient height to fill pocket 23'. Pocket 23 also serves as a water level indicator so that the level within receptacle 15 110 may be ascertained at all times without raising the cover 29. Should this level rise too high, the water will first drip over lip 26 to warn the attendant and if this warning is not heeded the water will overflow through 115 pocket 23 and prevent the water level 40 from rising to or above the food support 36, to be described.

Cork or like closure means 28 may be removed should it be desired to lower the 120 water level or drain the chamber 39.

A food or like support 36, made of non-porous material such as metal, is positioned within the receptacle 15 and is supported above and substantially parallel with the 125 bottom 16 by means of legs 37. Legs 37 are of such a height as will maintain support 36 above the maximum water level. Support 36 is provided with aperture 38 approximately in the center thereof to permit the 130

insertion of a finger for the purpose of lifting said support out of receptacle 15.

I gain results by the use of my improved cover never before gained to my knowledge. 5 Other types of coolers of this class either depend on drawing water from the sides of the receptacle by actual contact therewith and the consequent capillary attraction, or else simply use the cover as a closure, not 10 attempting to utilize it as a cooling agent. In the first case, the method precludes the allowance of a loosely fitting cover and consequent circulation through the cooler. Furthermore, it has been shown that it is practically 15 impossible to depend on capillary attraction to draw water in any quantity to the top edges of the receptacle and hence no appreciable amount of water can be drawn from the side walls into the cover. In the 20 second case, a cooling area of generous proportions has been overlooked.

In practice, I pour water over the entire surface of the porous material 33, comprising the major portion of the cover 29 and 25 find that this will maintain such material 33 in a moist state during the entire period between the charging and re-charging of the reservoir 21. The resulting evaporation gives me a cooling unit independent of the 30 water supply carried in reservoir 21 and chamber 39 and serves to greatly increase the efficiency of the cooler as a whole.

I wish to state that the cooling principle as applied to the introduction of water 35 through the top of the cooler's walls may be applied to food or like coolers irrespective of size, even to entire rooms used for storing meats and the like.

While I have herein shown and described 40 one specific embodiment of my invention, I

do not wish to be limited thereto except for such limitations as the claims may import.

I claim:

1. In a food or like cooler, a receptacle of concrete or like porous material, a reservoir 45 formed integral with the upper walls of said receptacle, said reservoir being constructed of a material of a relatively low degree of porosity and said walls being constructed of a material of a relatively high 50 degree of porosity whereby water may pass by capillary attraction from said reservoir into said side walls and whereby such passage is restricted.

2. In a food or like cooler, a receptacle of 55 porous material, a water chamber within said receptacle, a water reservoir positioned approximately at the top of the walls of said receptacle, a cover for said receptacle, said cover comprising a pan of non-porous material, concrete or like porous material substantially filling said pan, and overturned edges on said pan extending partially over said porous material.

3. In a food or like cooler, a receptacle of 60 porous material, a water chamber within said receptacle, a water reservoir positioned approximately at the top of the walls of said receptacle, a cover for said receptacle, said cover comprising a pan of non-porous material, a channel member extending across and secured to said pan, a handle secured to said 65 pan, and porous material substantially filling said pan.

In testimony whereof, I hereby affix my 70 signature in the presence of two witnesses.

FRANK O. ADAMS.
